UNITED STATES PATENT OFFICE

NATHAN LEVIN, OF TRENTON, NEW JERSEY, ASSIGNOR TO H. BRINTON COMPANY, OF PHILADELPHIA, PENNSYLVANIA, A CORPORATION OF PENNSYLVANIA

PATTERN MECHANISM FOR CIRCULAR RIB KNITTING MACHINES

Application filed August 26, 1931. Serial No. 559,579.

My said invention relates to a pattern mechanism and it is an object of the invention to provide a pattern mechanism controlled by a card or band of paper or other suitable material, which mechanism embodies various features of advantage, such as simplicity of construction, certainty of control of parts, direct and positive actuation, etc., all as will appear from the subjoined 10 description.

A further object of the invention is to provide an improved element in the nature of a detent for certain actuating devices combined with a feeler for the pattern card.

15 My pattern mechanism is particularly advantageous in connection with the control of a circular multiple-feed rib knitting machine and it has been illustrated in connection with elements of such a machine but it is 20 to be distinctly understood that the invention is not limited to the control of such a machine but may be used in various other relations.

Referring to the drawings, which are made 25 a part of this application and in which similar reference characters indicate similar parts.

Fig. 1 is a plan of my improved mechanism as applied to a machine of the character 30 above indicated.

Fig. 2, an elevation of the same viewed from the right; i. e., the bottom of the sheet in Fig. 1,

Fig. 3, a similar elevation viewed from 35 the left; i. e., the top of the sheet in Fig. 1,

Fig. 4, an elevation viewed from the front of the machine; i. e., the foot of the sheet in Fig. 1, with parts omitted,

Fig. 5, a vertical section through parts 40 shown in Fig. 1,

Fig. 6, a similar view with parts in a different position,

Fig. 7, a view similar to Fig. 5 with parts in still another position,

45 Fig. 8, a plan of controlling means for dial and cylinder cams, said figure also illustrating certain of the cams in one of their positions,

Fig. 9, an interior elevation of cylinder 50 needle cams,

Fig. 10, a plan of yarn feeding mechanism, Fig. 11, an elevation of the same, looking radially inward toward the axis of the machine,

Fig. 12, a similar view of stitch length 65 controlling mechanism for a cylinder stitch cam,

Fig. 13, a similar view of controlling mechanism for a latch clearing cam,

Fig. 14, a similar view of dial cam controlling mechanism,

Fig. 15, a section on line 15—15 of Fig. 14, and

Fig. 16, a detail of a part of the pattern band, which may be of paper or other suitable material.

In the drawings, reference character 20 indicates the stationary table or base of a circular knitting machine having a rotary cam ring 21 on which are located four standards 22 (Fig. 8) for supporting a crossbar carrying the usual dial post for the dial indicated at 22' in which are located needles 22" coating with cylinder needles 23' in the needle cylinder 24', the dial needles being actuated by cams on the dial cam cap 23. Said standards 22 also support the table carrying the yarn bobbins for making the fabric.

The cylinder needle cams include stitch 80 cams 24, needle elevating cams 25 for clearing the latches prior to taking yarn, a special needle elevating latch-clearing cam 26 at a point where no yarn is fed, a cast-off cam 27 (which last two-named cams may be omitted as hereinafter described) and other conventional guard cams, etc., as usual in machines of this type. The dial cam cap carries a needle projecting cam 28 movable to a welt position indicated in dotted lines in Fig. 8 or to an 85 intermediate tuck position, a needle advancing cam 29, a dial stitch cam 29' and other guard cams, etc., as usual.

The controlling mechanism for the various conventional cams above referred to includes 90 means whereby the needle elevating cam 25 may be held in either knitting position or tuck position, said means comprising a post 30 to which the cam is secured (Figs. 8, 14 and 15). This post has secured thereto an 95 100

outwardly projecting arm 31 having a cam face at 32 whereby the post may be raised by actuating means hereinafter described, in opposition to the action of a spring 33, which normally holds the cam down in the tuck position. A detent pivoted at 34 has a low face at 35 and a high face at 36 for engagement with a finger 37 on the arm 31. A spring 38 tends to force the detent 33' outward into a position where the face 36 supports the finger 37 and connected parts in the knitting position of cam 25.

The corresponding needle projecting cam 28 on the dial at the feed now being described is of the type in which the needles are positively moved inward to the tuck or welt position with the pivoted cam, said cam having for this purpose a needle path 39 and therefore the movement toward the welt position must be in two steps to prevent the formation of holes in the fabric, as would occur if these needles were moved immediately from knitting position to welt position where no yarn is taken by them. The controlling means for this cam includes a link 40 (Figs. 8 and 14) connected to a rockarm 41 on a shaft 42 about which is located a torsion spring 43' which tends to turn the shaft so as to move the cam 28 toward the welt position. The shaft is held against the action of the spring by a pair of latches 43 and 44, latch 44 holding the parts in a position corresponding to the knitting (or fully projected) position of the cam 28 whereas the latch 43 is adapted to hold the parts in a position corresponding to the tuck position of said cam. The latches are journaled on a sub-shaft 46 and the latch 44 includes an integral abutment 45 while latch 43 includes an integral abutment 47 extending outwardly into the path of pattern elements hereinafter described for releasing the respective latches from a rockarm forming the inner end of a bent lever 47' adjacent the lower end of shaft 42 and generally similar to rockarm 41. A torsion spring 48 is wound about shaft 46 and is attached to latch 44 for holding it in operative position in engagement with the lower rockarm of shaft 42. A similar spring 49 is in engagement with hook 43 for similarly holding it in such operative position. It will be evident that the latch 44 is to be released first, whereupon the dial needle cam 28 may move to the tuck position and thereafter the latch 43 is released to permit the cam to move to welt position. For this purpose the lug 45 is first engaged by pattern mechanism hereinafter described and thereafter the lug 47 is engaged by another element of the pattern mechanism. The outwardly extending arm of bent lever 47' forms an abutment by engagement with which an element of the pattern mechanism restores the dial cam 28 to needle projecting position, whereupon the other arm of bent lever 47' is engaged by hook 44 and held in such position,

the hook 43 assuming the position shown in Fig. 8, so that it will hold the cam at knitting position whereas when latch 43 is released the latch 44 will be in a position to catch and hold the parts with the cam in tuck position. All the abutments mentioned are of course supported on the revolving cam ring.

A special control is provided for lengthening the stitches on the cylinder needles at a feed where they are to knit in making a welt, it being understood that the welt may be knit at more than one feed, in which case a similar means will be provided for controlling the stitch cams at such other feeds. The stitch lengthening means for the cam 24 (Figs. 8, 12) comprises a vertically movable support 50 having a radially extending arm 51 with an upper cam face at 52 and also having a circumferentially extending arm 53 with an opening through which extends a screw 54 about which is located a compression spring underneath said arm (not shown) said spring tending to raise the shaft 50 and the stitch cam into its normal position. A pair of shafts 55 and 56 are located adjacent post 50, one of said shafts carrying a rock-arm 57 with a bolt 58 in its outer end positioned to engage the cam at 52 and force the post 50 and its attached cam 24 downward to lengthen the stitches at the time when the dial needle cam is in welt position, at which time the stitches of the cylinder needles are drawn over the needle verge instead of being measured over the dial needles. The shafts 55 and 56 are connected by pinions 57 and 58, and are provided respectively with rockarms 59 and 60, these rockarms being at different elevations. It will be evident that if an element of pattern mechanism engages rockarm 59 and moves it clockwise in Fig. 8, the shaft 55 will be turned so as to move rockarm 57 clockwise and cause its bolt 58 to depress the post 50 and the attached cam 24, thereby lengthening the stitches of the cylinder needles at this feed.

Subsequent engagement of another pattern element with abutment 60 will move the bolt off the raised part at the outer end of arm 51, due to clockwise movement of rockshaft 56 and consequent counterclockwise movement of rockshaft 55 by reason of interengagement of pinions 57 and 58.

For controlling the special latch-clearing cam 26 to clear the latches of the cylinder needles prior to casting off for making a selvage welt, this cam is mounted on a post 61 (Figs. 8 and 13) which is normally forced downward by a spring 62 for holding the cam in the position of Fig. 9. This post is provided with a projecting arm 63 having at 64 a cam face for engagement by an element of pattern mechanism to raise the post and the cam into latch clearing position. When the post is so elevated a detent 65 is moved

clockwise about its pivot 66 by a spring 67 to carry a pin 68 underneath a face at 69 on the radially projecting arm 62 (which face is lower than the face at 70 against which the pin 64 normally rests). The pin 68 thereupon holds the posts 61 and the cam 26 in elevated position for clearing the latches of the cylinder needles at this point until a pattern element strikes the outwardly projecting portion of the detent to force it back against the tension of its spring 67, whereupon the post and its attached cam move downward to a position in which the cylinder needles are not elevated sufficiently to clear their latches.

5 In addition to the parts so far described the machine includes at each feed a yarn guide and a clamp and cutter for the yarn, it being necessary to remove the yarn from the needles when the feed is thrown out of action, since otherwise the cylinder needles would continue to take the yarn, as they are at tuck position when not knitting, there being no welt position in this machine for the cylinder needles. For this purpose yarn controlling mechanism of the type shown in the patent to Larkin 1,359,258, November 16, 1929, is herein disclosed, said mechanism including a pair of posts 69 and 70 (Fig. 8) for supporting the mechanism shown in Figs. 10 and 11. On these posts is mounted a plate 71 to which is secured an inclined plate 72 by means of an intermediate plate 73. The inclined plate has mounted thereon a yarn guide 74 pivoted at 75 and provided with a pair of abutments 76 and 77 for engagement by elements of the pattern mechanism, these abutments being located at different levels as shown in Fig. 11. The spring pressed detent 78 is adapted to engage either one of a pair of notches at 79 to hold the yarn guide in either its idle or its active position. The inclined plate 72 has secured thereto a plate 80 to which is secured a bracket 81 carrying a pivot 82 for a movable shear blade 84 coacting with a fixed shear blade, as in said patent, these blades being held together by means of a compression spring 86. A laterally projecting guide plate 87 has an opening for a plunger 88 connected by a link 89 to a pivot 90 on the movable shearblade which is held normally in closed position by a spring 91. When the yarn is to be put out of action a member of the pattern mechanism hereinafter described engages the plunger 88 to open the clamp and cutter. When the yarn guide now moves out of feeding position it carries its yarn into the open shear and upon release of the plunger 88 the spring 91 will close the shear so as to sever the yarn and hold the free end of the supply yarn.

The various abutments above enumerated are arranged at different heights, such that a pattern device located at the bottom of the stack to engage and release the latch 92 to unlatch the cylinder needle elevating cam

25 can also strike latch 65 to unlatch clearing cam 26. The next higher abutment may engage arm 31 to raise the cylinder needle clearing cam 25 to latched position and may also strike latch 65 to unlatch clearing cam 26. The next abutment engages the cam face on arm 64 to raise cylinder needle clearing cam 26 to latched position. The next pattern element strikes the abutment 47 of hook 43 to permit dial cam 28 to go to tuck position and also strikes arm 59 to depress the stitch cam 24 for lengthening the cylinder stitches in making a selvage welt. The fifth pattern element strikes abutment 45 to release hook 44 and permit the dial cam to go to welt position. The sixth pattern element strikes arm 47' to move the dial cam 28 to knitting position and also strikes arm 60 to move bolt 68 off the cam surface on arm 51 permitting the stitch cam 24 to assume normal knitting position. The seventh pattern element has no cooperating abutment in the machine illustrated but may be used for actuating abutments of other devices for special purposes. The eighth and ninth pattern elements engage abutment 77 and plunger 88 respectively to move the yarn finger 74 out of feeding position and to operate the clamp and cutter for cutting off the yarn and holding its free end, and the ninth pattern element at a later time engages abutment 76 to move the yarn finger back to feeding position.

At each of the feeds of a multi-feed knitting machine there will be provided mechanism such as shown in Figs. 1, 2 and 3, including a bracket 100 attached to the machine frame 20. For engagement by a cam at each feed there is a lever 101 pivoted at 102 and having a roller at 103 (Figs. 1 and 4) for engagement by each of a series of cams 104 one for each feed secured to the gear ring for rotation with said ring and with the cam ring. It will be noted that the advancing side of the cam is formed as a relatively gradual rise, while the remote side is more steeply pitched, it being necessary for the roller 103 and certain parts actuated by lever 101 to return to innermost position between successive feeds.

A housing indicated at 105 (Figs. 1, 2, 3, 5, 6, 7) is mounted on the bracket 100, said housing being secured to the bracket by bolts 107, said housing extending inward over the bed 20. The bracket 100 is fastened to the side frame 106. At the inner end of the housing guide screws 108 extend from top to bottom thereof for guiding a group or stack of slides 109 to 117, which slides are provided at their outer ends with suitable abutments for engagement with the respective lugs and arms shown in Figs. 12 to 15 these abutments in some instances having inclined outer faces as shown at 118 in Fig. 1 or cam faces above or below as at 119 in the

- same figure. The slides are provided with slots as at 120 to receive the guide pins 108, and springs 121 serve to draw them into a position remote from the abutments on the cam ring except inasmuch as they are prevented from so moving by means hereinafter described. For pushing the horizontal slides 109 to 117 inward toward the cam ring I have provided vertical or upright slides shown at 122 in Fig. 1, the outline of one of these slides being shown in detail in Figs. 5 to 7. At their forward or inner ends the slides 122 are provided with projections indicated respectively at 123, 124, 125, 126, 127, 128, 129, 130 and 131 (Fig. 2) each of these projections being individual to a particular one of the horizontal slides, so that any vertical slide that is held in the position indicated in Fig. 2 will hold the correspondingly horizontal slide in the inward or operative position relatively to such abutments on the cam ring as are located at a level corresponding to that of such horizontal slide. It will be noted that Fig. 2 shows a forward position of the vertical slides and Fig. 3, a rearward position. The vertical slides are moved backward or outward by springs 121 in the action of such springs on the horizontal slides. For moving them inward I provide a U-shaped rocker 132 pivoted at 133 and having an arm 134 extending downward below such pivot. A spring 132' moves the rocker counterclockwise. Adjacent its upper end the rocker is provided with a plurality of pins 135, one for each of the vertical slides and positioned for engagement therewith. These pins are preferably screw-threaded for adjustment and may be held in adjusted position by screws 136 (Fig. 2). At the lower end of arm 134 a substantially L-shaped push bar 137 is pivoted to the arm for movement into or out of position to be engaged and actuated by a pin 138. The pin 138 extends laterally from a collar 139 secured by a set screw 140 to a reciprocating bar 141 mounted in bearings at 142 and 143. At its inner end the bar 141 is attached by a yoke 144 to lever 101 for moving the bar in one direction and a spring 145 serves to hold the bar in its innermost position, said spring also holding the roller 103 against the periphery of the rotating member which carries the cams 104.
- It will be seen that each time a cam 104 passes a feed of the machine the reciprocating rod 141 will be moved outward due to the action of the lever 101 and will cause the rocker 132 to move the vertical slides inward if the push bar 137 is in position to be actuated by the pin 138 on the reciprocating rod.
- 60 The factor just mentioned and other mutable factors are determined for each of the pattern mechanisms at the respective feeds by means of a pattern band 146 having pattern openings 147 (Fig. 16) in any desirable arrangement to produce the desired effects and also having driving apertures 148 along opposite edges thereof. This pattern band is trained over a drum 149 (Figs. 2 and 5 to 7), the drum having pins 150 to engage in the driving openings 148. The pattern drum is mounted for rotation on a stationary shaft 151 which rotation is frictionally resisted by a resilient spider 152. The pattern drum is driven by a ratchet 152 secured thereto and a pawl 154 forced toward the ratchet by a spring 155 engaging at one end a pin 156 on a bracket 157 and secured at the other end to a pin 158 on the pawl. The pawl is pivotally supported upon a rockarm 159 forming one arm of a bent pawl lever whose other arm is indicated at 160. Arm 160 carries a pin 161 adapted to rest either on a high face 162 or on a low face 163 of a plate 164 fixed to a collar 165 which is secured to the reciprocating bar 141 by set screw 166 or the like. It will be seen that in its outward movement the plate 164 elevates the pin 161 by means of the cam face between the two faces 162 and 163, thereby actuating the ratchet positively through the pawl 154, and that the spring 155 not only pulls the pawl 154 down with the ratchet but also draws the bent lever in a direction to hold its pin 160 down on the plate 164.
- For determining which, if any, of the horizontally movable slides 109 to 117 shall remain in its inner abutment-actuating position I provide a plurality of feelers 167 coacting with the pattern band, each pivoted at 168 (Fig. 2) and each having a pin at 169 (Figs. 5 to 7), which pins are preferably alined in correspondence with the alined openings in the pattern band at any of the pattern controlling positions of the band. The drum has annular grooves at 170 underneath the openings 147 in the pattern band, hence after each movement of the pattern band if the band has openings directly underneath the row of pins 169, such pins can pass through the openings and permit the feeler to fall to the position indicated in Fig. 6 whereas at a point where there are no openings the feeler will remain in the position indicated in Fig. 5. To raise a pin 169 out of engagement with an opening in the band and also to prevent wear on the band because of pin 169 dragging on its surface I provide means for lifting the feelers into the position of Fig. 7, such means consisting of a paddle 171 pivoted at 172, said paddle extending across the row of feelers and having an inwardly extending arm 173. The arm and the paddle are rigidly attached to the spindle 172, as by a set screw 174. (Fig. 2.) The paddle is actuated on the inward or return movement of the reciprocating rod 141 by means of a cam face on a plate 175 to tilt the feelers about their pivot 168 against the tension of springs 176.
- Th cam plate 175 is fixed to the collar 139 so as to reciprocate with the rod 141, thus

moving the paddle upon inward movement of said rod so as to cause it to strike a downwardly extending lug 177 on each feeler and move the same to the position shown in Fig. 7.

5 In addition to the features already described it should be noted that each feeler 167 has a rearward extension 178, which extension is considerably below the pivot 168 at its lowest point, where the spring 176 is connected to the feeler, whereby also said spring will pull the feeler down, i. e., counterclockwise about its pivot. Another spring 179 is attached at one end to this extension and at its other end to a detent 180 independently 10 pivoted on the spindle 168 and adapted to engage at its forward end a shoulder 181 on one of the vertical slides 122, it being understood that there is one feeler and one detent for each of said slides. The feeler has a face 15 at 182 upon which the detent rests at certain times. The feelers have their outer ends guided by a comb 183 (Figs. 2 and 4) for holding them in proper position. It will be seen that the paddle 171 moves all the feelers 20 from the position of either Fig. 5 or Fig. 6 to that of Fig. 7 at each feed at each rotation of the machine and then permits them to return to either of the positions of Figs. 5 and 25 6, according to whether or not the pattern band presents openings underneath the respective pins 169. The detents move clockwise with the feelers to a position somewhat lower than that indicated in Fig. 5 except in case of such detents as are in engagement 30 with shoulders 181 of vertical slides 182. A detent so engaged, as illustrated in Fig. 7, will maintain its position due to the friction of the parts, the spring 179 stretching at this time, and the respective positions of parts 35 40 will be maintained until the rocker 132 moves all the vertical slides inward to an extent indicated by the clearance between shoulder 181 and the adjacent end of the detent. Prior to this the paddle 171 has been released by 45 cam 175 so that the detents which are not in engagement with shoulder 181 bear against the face directly below the shoulder and as the slides 122 are moved inward those detents corresponding to feelers which are permitted 50 to drop to the position of Fig. 6, owing to the presence of openings in the pattern band, will move to the position of Fig. 6 during the time elapsing while the vertical slides 55 are moving forward a distance corresponding to the clearance indicated in Fig. 6 between the detent and the coacting shoulder. When rocker 132 now moves back counterclockwise the vertical slides and the corresponding horizontal slides are moved outward by 60 springs 121 excepting that those slides whose detents are in the position shown in Fig. 6 can move only a distance corresponding to the slight clearance shown in said figure, after which they are held in the position of 65 Fig. 7, as are also their corresponding hori-

zontal slides, so that the abutments located at the same height as these respective horizontal slides will be actuated as the next cam set passes the pattern unit.

A pattern chain 184 passes over a sprocket 185 on the stationary shaft 151. The sprocket is driven by a ratchet 186 actuated by a pawl 187 carried by a rockarm 188 secured to or integral with a rockarm 189. An idler ratchet 186' adjacent ratchet 186 has 70 deep and shallow teeth of well-known type to prevent over-frequent actuation of ratchet 186. Rockarm 189 is provided with a pin 190 positioned to rest either on an upper face 191 or on a lower face 192 of a plate 193, said faces being connected by a cam incline. The cam plate 193 is secured to a collar 194 fixed to the reciprocating bar 141, so that the sprocket will move one step at each reciprocation of said bar except as prevented by idler ratchet 186'. The chain is provided on some 75 of its links with plates 195 for engaging a lug 196 on a lever 197 pivoted at 198. At its forward end this lever is connected to a link 199 pivoted at its lower end to the L-shaped push bar 137, whereby the push bar will be held out of operative relation to pin 138 when a high place on the chain engages the lug 196, at which time the rocker 132 will therefore 80 not be actuated. The paddle-actuating rock-arm 173 carries a pin 200 (Figs. 1 and 3) in the line of movement of the L-shaped push bar when the same is elevated, whereby the paddle 171 will be held in its extreme clockwise position referring to Fig. 3 or in its 85 extreme counterclockwise position referring to Figs. 5, 6 and 7, so that it will hold the feelers away from the pattern, any detents 90 which are in engagement with vertical slides 122 however remaining in such engagement 95 by reason of the expansibility of springs 179. 100

The idling mechanism just described for idling the push bar 137 and the feelers serves also to idle the pawl 154 for driving the ratchet 149 due to the fact that a pin 201 110 (Figs. 1, 2, 3, 4) extends over the top of lever 197, so that when the lever is raised to the position shown in Fig. 3 the pin will also lift the pawl 154 out of engaging position with reference to its ratchet.

In making a welt on a rib knitting machine it has always been considered necessary to provide means at a distance from a feed for clearing the latches of one set of needles, this set being usually the cylinder needles in a 120 circular ribber. It is of great advantage, particularly in a multiple feed circular ribber such as herein shown and described, to economize space on the cam ring and many expedients have been proposed to this end with the result that in the larger machines the number of feeds is now much larger than was true in earlier days for a machine of the same circumference, whereby production has been 125 greatly increased. Now with a machine such 130

as here shown I have found that the latch-clearing cam 26 and associated coacting parts may be dispensed with, thus reducing expense and saving very valuable space on the 5 cam ring. According to my invention I clear the latches of the cylinder needles by throwing the yarn-guide to idle position, moving the dial needles to the welt position and holding them there while casting off the 10 stitches of the cylinder needles by the ordinary operation of the needle-raising (latch-clearing) cam 25 and the needle-lowering (casting-off) cam 24.

It will be obvious to those skilled in the 15 art that many changes may be made in the devices herein shown and described, all without departing from the spirit of the invention and therefore I do not limit myself to what is shown in the drawings and described 20 in the specification, but only as indicated in the appended claims.

Having thus fully described my said invention, what I claim as new and desire to secure by Letters Patent is:—

25 1. In a pattern mechanism, a feeler having a projection for entering a perforation in a pattern, and a detent combined with said feeler said detent being movable with the feeler and also having movement independ- 30 ently thereof.

2. In a pattern mechanism, a pivoted feeler having means to enter a perforation or recess in a pattern, a detent pivoted coaxially with the feeler, means for moving the feeler 35 and the detent simultaneously, and resilient connections between said detent and said feeler whereby they may also be moved independently of each other.

3. In a pattern mechanism, a pattern band, 40 a feeler having a pin for entering a perforation in said band, means for moving the feeler toward and from the pattern band, a selective device, a detent movable with the feeler into or out of operative relation to said 45 selective device, and resilient connections between said detent and said feeler to permit the detent to remain in engagement with said selective device independently of the operation of the feeler.

50 4. In a pattern mechanism, a vertical series of horizontal slides having means at one end for acting on devices to be selectively controlled, a series of upright slides each operatively connected to a horizontal slide, 55 means for advancing said slides intermittently, means for retaining selected slides in advanced position including a pattern band and feelers coacting therewith, means for moving the feelers intermittently out of engagement with the pattern band, and pattern-controlled means for idling both of said intermittently operating means.

5. In a pattern mechanism, a vertical series of horizontal slides having means at 65 one end for acting on devices to be selective-

ly controlled, a series of upright slides each operatively connected to a horizontal slide, means for advancing all the slides intermittently, means for retaining selected slides in advanced position including a pattern band and feelers coacting therewith, means for advancing the band to bring successive portions thereof into operative relation with said feelers, means for lifting the feelers before the band is advanced, and pattern-controlled means for idling the slide-advancing means together with the feeler-lifting means and the band-advancing means. 70 75

6. In a pattern mechanism for knitting machines, a series of superposed elements, a laterally-extending series of elements each having means for actuating an element of said first-named series, means for actuating all the elements of the second series intermittently whereby all the elements of the first series are also actuated, means for retracting all the elements of both series, and pattern-controlled means for retaining selected elements of said first series in actuated 80 85 position. 90

7. That method of making a selvage welt on a multiple feed independent needle rib knitting machine having a series of needles crossing another series of needles for making ribbed work comprising throwing out the 95 yarn at a feed, holding the needles of one series in welt position at said feed, and casting off the stitches of the other series of needles at said feed thereby stopping the knitting operation at said feed while continuing to knit at other feeds. 100 105

8. In a multiple feed independent needle rib knitting machine having rotating cylinder and dial cams at each feed and abutments connected thereto, the combination of a perforated pattern band on the fixed machine frame, a horizontal shaft providing an axis for the band, cams on a rotating part of the machine adjacent each feed, a reciprocating element at each feed operated by said last-named cams, connections from said reciprocating element to said pattern band for moving the same about said axis, and connections from the pattern band for acting on 110 115 said abutments. 120

9. In a multiple feed independent needle rib knitting machine having rotating cylinder and dial cams associated with yarn-guiding, yarn-cutting and yarn-clamping means at each feed and abutments connected thereto, the combination therewith of a perforated pattern band on the fixed machine frame, a horizontal shaft providing an axis for the band, cams on a rotating part of the machine 125 adjacent each feed, a reciprocating element operated at each feed by said last-named cams, connections from said reciprocating element to said pattern band for moving the same about said axis, and connections from 130

the pattern band for acting on said abutments.

10. In a multiple feed independent needle rib knitting machine having rotating cylinder and dial cams associated with yarn-guiding, yarn-cutting and yarn-clamping means and abutments connected thereto, the combination therewith of a perforated pattern band on the fixed machine frame at each feed, a horizontal shaft providing an axis for the band, cams on a rotating part of the machine adjacent each feed, a reciprocatory element at each feed operated by said last-named cams, connections from said reciprocatory element to said pattern band for moving the same about said axis, and connections from the pattern band for acting on said abutments, said connections including a series of superposed slides each having means for acting on such abutments as are at its individual level.

11. In a multiple feed independent needle rib knitting machine having rotating cylinder and dial cams associated with yarn-guiding, yarn-cutting and yarn-clamping means at each feed and abutments connected thereto, the combination therewith of a perforated pattern band on the fixed machine frame, a horizontal shaft providing an axis for the band, cams on a rotating part of the machine adjacent each feed, a reciprocatory element at each feed operated by said last-named cams, connections from said reciprocatory element to said pattern band for moving the same about said axis, connections from the pattern band for acting on said abutments, said last-named connections including a series of superposed slides each having means for acting on such abutments as are at its individual level, and a series of vertical slides situated radially outward from said superposed slides, said vertical slides having abutments at different levels to coact with individual horizontal slides.

45 12. In a multiple feed independent needle rib knitting machine having rotating cylinder and dial cams associated with yarn-guiding, yarn-cutting and yarn-clamping means at each feed and abutments connected thereto, the combination therewith of pattern mechanism including a perforated pattern band on the fixed machine frame, a horizontal shaft providing an axis for the band, cams on a rotating part of the machine adjacent each feed, a reciprocatory element adjacent to the pattern mechanism operated by said last-named cams, connections from said reciprocatory element to said pattern band for moving the same about said axis, connections from the pattern band for acting on said abutments, said connections including a series of superposed slides each having means for acting on such abutments as are at its individual level, a series of vertical slides situated radially outward from said super-

posed slides, said vertical slides having abutments at different levels to coact with individual horizontal slides, means for advancing all the slides, and means for holding selected slides in advanced position.

70 13. A device as in claim 12, with means operating on a pattern mechanism between the movement of successive feeds past the same to advance the slides, to hold selected slides advanced and to return non-selected slides to inoperative position.

75 14. A device as in claim 12, with means operating on a pattern mechanism between the passing of successive feeds thereby to advance the slides, to hold selected slides advanced and to return non-selected slides to inoperative position, and pattern means in connection with each pattern mechanism for intermittently preventing operation thereof while permitting previously selected slides to remain in operative position.

80 15. In a circular knitting machine, a rotary cam ring, vertically-spaced selectively operable devices on said cam ring, a series of vertically-spaced elements on a stationary part of the machine, a series of elements arranged circumferentially of the machine and individually related to said vertically spaced elements, means for advancing the elements of said second series toward said cam ring whereby their individually related elements in the first series are operatively positioned for actuating said selectively operable devices, pattern-controlled means for holding selected advanced elements in advanced position, and means for retracting the advanced elements which are not so held.

85 16. In a circular knitting machine, a support rotatable about the axis of the machine, a fixed support, vertically-spaced abutments on one of said supports for controlling the knitting action, a vertical series of devices on the other support each movable into operative position for actuating an abutment at the same level therewith, a circumferential series of devices each operatively related to one of the devices of said vertical series for moving it into operative position and holding it therein, and pattern mechanism for controlling the action of said devices on said abutments.

- retracting the advanced slides, and detents controlled by said paper pattern band for selectively holding advanced slides in advanced position.
- 5 18. In a multiple-feed circular knitting machine, a cam ring having a plurality of feeds, a cam on the cam ring adjacent to each feed, a vertical series of abutments on the ring adjacent to each feed for controlling the knitting action at said feed, pattern mechanism on the frame of the machine including a vertical series of actuators at levels corresponding to the levels of the individual abutments of said series, means for advancing said actuators into operative relation to said abutments, and pattern means operated by said cams on the cam ring for selectively maintaining said actuators in operative position relatively to the correspondingly located abutments. 70
- 10 19. In a multiple-feed circular knitting machine, a cam ring having a plurality of feeds, a cam on the cam ring adjacent to each feed, a vertical series of abutments on the ring adjacent to each feed for controlling the knitting action at said feed, pattern mechanism on the frame of the machine including a vertical series of actuators at levels corresponding to the levels of the individual abutments of said series, pattern means operated by the cam on the cam ring for selectively maintaining said actuators in operative position relatively to the correspondingly located abutments, said pattern means including a radially movable bar, a horizontal shaft, means operated by said bar for turning said shaft to move said band, means operated by said bar for advancing said actuators, and means operated by said pattern band for selectively determining the actuators to be held in advanced position. 80
- 15 20. In a circular multiple-feed independent needle rib knitting machine, a stationary needle cylinder, a stationary dial, cams for cylinder and dial needles, control arms for varying the operation of the machine, a stack of horizontally movable elements for selectively actuating said control arms, a circumferentially arranged series of upright elements each operatively related to a horizontally movable element, means for advancing all said elements toward control-arm-actuating position at each rotation of the machine, and pattern-controlled means for idling said last-named means. 85
- 20 21. In a circular multiple-feed independent needle rib knitting machine, a stationary needle cylinder, a stationary dial, cams for cylinder and dial needles, control arms for varying the operation of the machine, a stack of horizontally movable elements for selectively actuating said control arms, a circumferentially arranged series of upright elements each operatively related to a horizontally movable element, means for advancing all of said elements toward control-arm-actuating position at each rotation of the machine, means for retaining selected horizontally movable elements in advanced position including a pattern band and feelers coacting therewith, means for moving the feelers away from said pattern band, and pattern-controlled means for idling both the element-advancing means and the feeler-lifting means. 90
- 25 22. In a circular multiple-feed independent needle rib knitting machine, a stationary needle cylinder, a stationary dial, cams for cylinder and dial needles, control arms for varying the operation of the machine, a stack of horizontally movable elements for selectively actuating said control arms, a circumferentially arranged series of upright elements each operatively related to a horizontally movable element, means for advancing all of said elements toward control-arm-actuating position at each rotation of the machine, means for retaining selected horizontally movable elements in advanced position including a pattern band and feelers coacting therewith, means for advancing the band step by step, means for lifting the feelers preliminary to advancing the band, and interconnected pattern-controlled means for idling the element-advancing means, the feeler-lifting means and the band-advancing means. 95
- 30 23. In a pattern mechanism, a pattern band movable about a horizontal axis, a vertical series of actuating devices each movable only in an individual horizontal plane, means for advancing all said actuating devices, and connections from said pattern band for holding said actuating devices in advanced position. 100
- 35 24. In a pattern mechanism, a pattern band movable about a horizontal axis, a vertical series of actuating slides each movable only in a horizontal plane, means for advancing all of said actuating devices together, means for retracting all of said actuating devices and connections from said pattern band for holding said actuating slides selectively in advanced position. 105
- 40 25. In a pattern mechanism, a pattern band movable about a horizontal axis, a vertical series of actuating devices each movable only in a horizontal plane, means for advancing said actuating devices selectively to operative position, said connections including elements movable in vertical planes, means on each of said element for advancing one of said horizontally movable devices, and means operable by said pattern band for holding a selected device in operative position. 110
- 45 26. In a pattern mechanism, a pattern band movable about a horizontal axis, a vertical series of actuating slides each movable in a horizontal plane only, means for advancing said actuating slides simultaneously to operative position, said connections in- 115

cluding a set of slides movable in vertical planes only and each operatively related to a horizontally movable slide, and means operable by said pattern band for holding actuating devices selectively in operative position.

27. In a pattern mechanism, a series of horizontally movable elements each having an actuating abutment, a series of elements movable in vertical planes for advancing the horizontally movable elements, and lugs on the elements of one set each lug being positioned to engage an individual element only of the other set.

15 28. In a pattern mechanism, a stack of slides each movable in a horizontal plane, an actuating abutment on each of said elements each abutment being reduced at a horizontal face to form a cam thereon, a series of elements each movable in a vertical plane to advance a slide, and a lug on each of said last-named elements each lug being operatively related to a different element in said stack.

In testimony whereof I affix my signature.

25 NATHAN LEVIN.
